UNITED STATES PATENT OFFICE.

THOMAS EYNON, OF ROCK ISLAND, ILLINOIS, ASSIGNOR TO WILLIAMS, WHITE & COMPANY, OF MOLINE, ILLINOIS, A CORPORATION OF ILLINOIS.

BOLT AND NUT ASSEMBLING MACHINE.

Application filed April 23, 1921. Serial No. 464,010.

To all whom it may concern:

Be it known that I, THOMAS EYNON, a citizen of the United States, residing at Rock Island, in the county of Rock Island and State of Illinois, have invented certain new and useful Improvements in Bolt and Nut Assembling Machines; and I do hereby declare the following to be a full, clear, and exact description of the invention, such as will enable others skilled in the art to which it appertains to make and use the same.

This invention relates to mechanism for automatically assembling threaded bolts with nuts.

15 The objects are to improve the organization and improve various elements thereof.

The invention consists in the combinations described in the specification, illustrated in the drawings and defined in the appended 20 claims.

In the accompanying drawings, in which like parts are indicated by like reference characters:

25 Figure 1 is a side elevation of a machine embodying my invention adapted to assemble nuts and bolts in a horizontal position;

Figure 2 is a plan view of the mechanism shown in Figure 1;

Figure 3 is a fragmentary end elevation 30 viewed from the right of Figures 1 and 2;

Figure 4 is a side elevation, without the bolt run, of a modified form of my improved machine adapted to assemble bolts and nuts in vertical position;

35 Figure 5 is a plan view of the machine shown in Figure 4;

Figure 6 is a plan view of the bolt conveyer and discharge end of bolt runway employed in the machine disclosed in Figures 40 and 5;

Figure 7 is a section through the base plate on line 7—7 of Figure 4 showing in elevation the bolt conveyer, bolt stop and nut seat;

45 Figure 8 is an elevation of the discharge end of the bolt run as seen looking in the direction of the arrow 8 in Figure 6;

Figure 9 is an elevation of the lower portion of the bolt run as seen looking in the 50 direction of the arrow 9 in Figure 6.

Figures 10 and 11 are, respectively, a longitudinal section and a face view of a bolt chuck or socket carried in the spindle, and adapted to engage and rotate square headed bolts;

Figures 12 and 13 are, respectively, a longitudinal section and a face view of a bolt socket adapted to engage and rotate round headed bolts.

In the embodiment shown in Figures 1, 2 and 3 of the accompanying drawings, 1 represents the machine base, which may be a casting that supports the operative mechanism. From the base 1 a plurality of posts or similar supports project upward for the purpose of sustaining and affording bearings for the several shafts of the operating mechanism, and for supporting the hoppers and other necessary parts of the machine to be later described.

The upward projecting supports 2, 3 and 4 have aligned bearings for the main power shaft 5, while the two supports 3 and 4 project higher than the support 2 and have aligned bearings for the longitudinally slidable bolt rotating shaft 6. Upon one extremity of the main power shaft 5, as shown, which preferably projects through the bearing support 2, are fast and loose pulleys 7 and 8, with which engages the main driving belt, not shown. Secured to shaft 5 between the uprights 3 and 4 are small and large gears, 9 and 10, respectively. Rising from the base 1, out of alignment with uprights 2, 3 and 4, is a bearing support 11 in which is secured a stub shaft 12 on which is journaled a large gear 13; the gear 13 may be secured to a shaft that turns in said support 11. Upon the front or left hand face of gear wheel 13, as viewed in Figure 2, are two cam ways 14 and 15. Upon the rear or right hand face of said gear 13 is another cam way 16. The said cam ways or cams effect the operations of certain essential mechanisms in proper timing with respect to each other in a manner to be presently described. Splined upon the shaft 6, between the uprights 3 and 4, so that said shaft 6 may move longitudinally but cannot rotate with respect thereto is a pinion 17, spaced from the uprights by hubs or spacing members 18. The shaft 6 is adapted to advance and simultaneously rotate a bolt b, which it is an object of the machine to thread into and assemble with a nut n; and in order that the bolt may be rotated by the shaft 6, said shaft has on its free end, as indicated at the right in Figures 1 and 2, a bolt chuck or socket for automatically engaging the head of a bolt and causing the bolt to rotate

100
105
110

as the spindle or shaft 6 advances in contact with the bolt head.

As will be apparent from the mechanism thus far described, when the driving belt is slipped onto the fast pulley shaft 5 will be rotated, and will impart a relatively slow rotation to the large gear 13 which carries the described cams 14, 15 and 16; and the bolt assembling spindle or shaft 6 will be 10 rotated at a relatively high rate of speed, advanced yieldingly, and the associated mechanisms operated in proper time.

In order to receive the bolts and nuts to be assembled, oppositely disposed hoppers 20 15 and 20^A are provided as indicated in Figures 1 and 2. The hopper 20^A is designed to receive the nuts which may be guided by gravity down the nut-run 22^A to the nut assembling position 22^B. This hopper 20^A and 20 nut-run 22^A are of known construction and need not be further described. An agitating device (not shown) may be provided if desired for facilitating the delivery of the nuts in a customary manner. The hopper 20 is 25 intended to receive the bolts. The said hopper has double inclined sides 21, rising from a pair of parallel guides 22 which are separated so as to allow the shanks of the bolts to hang downward between them with the 30 heads of the bolts resting on the guides 22. Said guides are inclined downward from the hopper toward the position to which the bolts are to be delivered and assembled with the nuts and constitute the bolt run. Both hoppers and runways are suitably sustained by upright supports rising from the base 1 and said supports may be adjustable in height, if desired, by making them extensible as indicated in the upright 23 shown in 40 Figure 3. At its lower end the bolt guiding passageway between the bolt guides 22 turns sharply at right angles so as to present a discharge opening toward the gear 13 as illustrated in dotted lines at 24 in Figure 2, 45 the end of outer guide 22 extending at an angle and curving downward as at 22^A, and the inner guide terminating short of the curved end of the other so as to permit a bolt to be pushed out of said runway between the 50 end of the inner guide and the outer guide and caused to fall onto receiving devices disposed to catch it whence it is conveyed or moved to assembling position. In order that the bolt in position to be ejected from the 55 lower end of the bolt runway may not escape accidentally but may be held in the lower end of the runway until positively ejected, a yielding or spring held plate 25 is so positioned as to retain the bolt at the bottom of 60 the runway unless the bolt is pushed laterally, said plate then permitting the bolt to escape. The plate 25 may be supported in any suitable manner, as for example, on the upper end of a bracket 26 secured to the inner or lower end of the nut run-way 22^A

from which said bracket extends to a point above and rearward of the lower end of the bolt-run.

Each bolt 5, as it is ejected from the bolt-run, falls upon suitable inclined receivers 70 27^A, 27^B on the landing plate 27. The receiver member 27^B is directly beneath the end of the bolt run at one side of the depending end of a bolt so that when said bolt is pushed from the chute its lower end will stop adjacent the member 27^B, while the head of the bolt will describe an arc about the edge of said receiver and the bolt will be tripped and caused to fall upon receiver members 80 27^A and 27^B in the prostrate position shown in Figures 1 and 2. A suitable abutment plate 28 is so positioned as to engage the head of the prostrate bolt and substantially determine its position longitudinally. The plate 28 is shown as mounted on the end of a bracket arm 29, which may be adjustable if desired.

In order to eject a bolt from the lower end of the bolt runway at the proper moment with respect to the general timing of the mechanism an ejector arm or plunger 30 is provided, the said ejector being so disposed and operated that when it moves to the left (as shown in Figures 1 and 2) the end of the ejector will push a bolt to the left with force enough to displace the spring retaining-plate 25 and cause a bolt to trip over the member 27^B. The said ejector 30 is attached in any suitable manner to the upper end of a lever 31, pivoted to fulcrum lug 32 on the base 1. The lever 31 is operated by a link rod 33 which is passed loosely through a hole near the upper end of the lever and carries a coil spring 34 between the lever and a nut or head 35 on the end of the rod. The other end of link rod 33 is connected to a lever arm 36 that is keyed to rock shaft 37 journaled transversely of the base 1 in bearing standard 3 and a bearing lug 38. To one end of rock shaft 37 is fixed an arm 39 which is urged upward by a spring 40, in order to force the bearing roller 41 on the arm 42, secured to the other end of the rock shaft, into yielding contact with the aforesaid cam 14 on the left hand face of gear 13, as viewed in Figure 2. By means of the ejector operating mechanism described the ejector movement will be properly timed, the ejector moved forward to eject the bolt by the positive engagement of the roller 41 with cam 14, and the spring 34 will cushion the ejector so that it may yield in case of abnormal obstruction to its advance, and no harm can result to the mechanism. The spring 40 restores the ejector, and holds the roller 41 against the cam. 110 The prostrate bolt is conveyed to assembling position by the means now to be described. The receiver members 27^A and 27^B on the landing plate for the prostrate bolt 115 120 125 130

incline inward toward the spindle or shaft 6. In order that the bolt may move to assembling position at the proper moment, two pins 42^a, 42^b, secured to a rock shaft 42 are erected in position alongside the bolt when the latter falls to the receivers. At the proper time in relation to the movements of the other parts of the machine, shaft 42 is rocked so as to turn pins 42^a, 42^b out of the way and allow the bolt to roll or be conveyed by gravity from the receiver members 27^a, 27^b to bolt holding devices to be presently described. The shaft 42 is suitably journaled in bearings 43 connected to landing plate 27. A crank arm 44 secured to one end of rock shaft 42 is connected by a link 45 to an arm 46 rigid on rock shaft 47, which is journaled transversely of the base 1 in bearing supports 4 and 11. Secured fixedly to rock shaft 47 is a crank arm 48 having a cam end 49 in the path of cam 16. To the end of rock shaft 47 that projects through the bearing support 4 is secured a rigid crank arm 50, and this arm is pressed upwardly by a spring 51 resting on a lug 52, as shown in Figure 1, in such manner that rock shaft 47 is rocked by the spring and keeps the cam end 49 of crank arm 48 pressed against cam 16. Automatically, therefore, the bolt on receivers 27^a, 27^b will be released and roll or slide therefrom to the bolt catching devices now to be described.

Journalized in bearing uprights 52, 53, is a pair of parallel rock shafts 54 to each of which are secured two spaced apart arms 55, 56, there being an arm 55 and an arm 56 on one rock shaft facing an arm 55 and 56, respectively, on the other rock shaft. The upper ends of said arms are beveled, as at 56^a, so that when the upper portions of the arms are in contact with the upper portions of companion arms two V-shaped bolt alining rests are formed, adapted to receive a bolt discharged from the receivers 27^a, 27^b and aline it with the nut seat and spindle 6. The V-shaped rests are disposed at a lower level than the receivers 27^a, 27^b and rock shaft 42, so that when said rock shaft 42 turns, lowering the pins 42^a, 42^b, the bolt will be guided onto the V-shaped rests between the arms 55 and 56. The rock shafts 54 are connected to a common operating means so that when one rocks the other will rock in unison in the opposite direction. One of said shafts 54 carries an arm 57 which is connected by a link 58 to arm 50 aforesaid on rock shaft 47, described as being operated positively in one direction by the cam 16 and in the opposite direction by the spring 51. The other shaft 54 is preferably connected to said rock shaft 47 by a duplicate mechanism. When the assembling operation is completed, the timing of the mechanism is such that the arms 55,

56 separate and allow the assembled bolt and nut to drop between them into a chute, such as 59, down which they slide to a receptacle or any place of deposit.

Two forms of chuck or bolt rotating members referred to hereinbefore as mounted at the end of sliding and rotating shaft or spindle 6 are illustrated in Figures 10 to 13. The bolt rotating member illustrated in Figures 12 and 13 comprises a head 60 having a tapered opening 61 to easily find and center a bolt head in the axial line of the spindle. The shank 62 is externally threaded as at 62^a or otherwise adapted to be secured in a hole made in the end of the shaft or spindle 6. The shank 62 is drilled from end to end and houses a coiled spring 63 one end of which rests against plug 64 inserted after assembling the spring. In the front end of the hollow shank is a shoulder 65. A plunger 66, having a rear stop flange 67, is pressed elastically forward by spring 63. In case the chuck is to engage round headed bolts sharp edged biting ribs (which may be steel inserts) 68, preferably three, are formed in the tapering cavity 61 and a cup-like seat formed in the end of plunger 66. If square headed bolts are to be seized the tapered cavity may be modified accordingly, as by forming four grooves to catch the corners of the head as it moves rearward into the tapered cavity of the chuck in head 60^a, as illustrated at 68^a in Figures 10 and 11. The forward end of the shaft or spindle 6 is equipped with a chuck of the type described and when a bolt rests in the V-shaped seats between the supporting arms 55-56 it will be alined with said chuck in the end of spindle 6. When the spindle advances and exerts pressure against the bolt head the latter will be gripped and compelled to rotate. When the spindle is retracted the spring-pressed plunger will release the bolt from the socket automatically.

On the rear end of shaft or spindle 6 is a shifter collar 70, engaged by a shifter lever 71, which, in the form shown, has a large orifice admitting passage of the shaft 5 and is secured to rock shaft 72 journaled in the bearing lugs 73 and 74. Secured to the other end of rock shaft 72 is an arm 75, having a substantially horizontally extending upper portion carrying a roller 76 that rests against the cam 15, and is held elastically in cam-engaging position by a spring 77. As a result, when the mechanism is in operation the spindle 6 will be forced forward by the spring 77 yieldingly so that the bolt chuck will engage the bolt head, the spindle at the same time rotating. The bolt will therefore be seized and advanced until the threaded end thereof engages the nut and is screwed into the latter. After this the spindle will be retracted by the positive action of the cam 15, leaving the as-

sembled bolt and nut in position on the V-shaped rests with the nut in the seat 22^b at the end of the nut runway 22^a.

Alined with the nut seat 22^b at the end of runway 22^a is a guide 78 in which moves a plunger 79, adapted to push the assembled bolt and nut to the left (as shown in Figure 2) in order to clear them from the nut seat so that they may drop between the arms 55,

10 56, after the spindle 6 has been retracted.

A rod 80 suitably guided is connected to plunger 79 by a cross bar 81, through a hole in which said rod is loosely passed, and a coil compression spring 82 surrounds the

15 rod 80 between said cross bar 81 and a head or nut 83 on the end of said rod. By means of the pressure of the compression spring 82 the plunger 79 will advance with a yielding pressure to eject the assembled bolt and

20 nut. If any obstruction occurs the spring will yield and the machine will continue to operate without danger of breaking any parts. Rod 80 is connected to a lever arm 84, adjustable in length if desired, to vary

25 the amplitude of movement of the plunger 79. Arm 84 is rigidly secured to a rock shaft 85 journaled in bearing upright 3. Secured to said rock shaft 85 is a cam-arm 86 the end of which is disposed to rest

30 against cam 15, and a spring 87 connected to arm 84, urges the cam-arm 86 against said cam, and serves to restore plunger 79 to its rearward position after the cam 15 has positively moved the rod 80 to the left (as shown in Figures 1 and 2) to eject the assembled bolt and nut. The arms 55—56, having separated, the assembled bolt and nut fall between the separated arms into the chute 59 and are collected beneath the discharge end

40 of said chute.

The form of the invention illustrated in Figures 4 to 9, inclusive, is adapted for use in assembling bolts and nuts where the bolts are too long to trip, properly, from the bolt runway of the mechanism illustrated in Figures 1, 2 and 3, and with those bolts that have odd-shaped heads that will not slide well on the bolt run or guide. In case bolts with heads that will not slide properly on the runs are to be handled, the bolt hopper and bolt run of the modified mechanism now to be described may be removed and the bolts be fed by hand into the bolt conveying device that places the bolt in alinement with the nut and bolt rotating spindle.

Referring now to Figures 4 to 9, inclusive: The base consists of an inverted pan-shaped casting 101 having upright bearing posts 102 and 103, in which are alined bearings sustaining a main power shaft 104, one end of which projects beyond post 102 and carries fast and loose pulleys 105 and 106. Bearing post 103 is higher than post 102 and has a second bearing above that of shaft 104, which may be a stub shaft or trunnion

on which are sleeved a pinion 107 and a gear wheel 108 rigidly connected to said pinion, or may be a hollow bearing supporting an axle projecting from the center of said pinion and gear wheel. On the end of shaft 104 that projects through the bearing post 103 is secured a pinion 109, arranged in mesh with the gear 108 whereby said gear 108 and pinion 107 may be rotated in unison by the main power shaft 104. Pinion 107 is 75 in mesh with a gear 110 secured to a shaft 111 journaled in bearing supports 112 and 113 rising from the base 101. The end of shaft 111 that is opposite that carrying gear 110 is provided with a crank 114, to which is pivoted one end of a link 115 the other end of which is connected to the nut hopper mechanism in order to facilitate the feed of the nuts from hopper 116 through the nut run or guide 116^a. The nut hopper and operating mechanism is of known construction and need not be further described. Fixed to one face of said gear 108 is a cam 117 for a purpose to be presently explained.

Bolted to the base 101 and extending upward therefrom is a hollow and slotted column 118. Two spindle bearing arms 119 project horizontally from one face of said column. Said arms have alined bearings for a bolt rotating spindle 120 which is provided at its lower end with one of the bolt engaging sockets illustrated in Figures 10 to 13. Said spindle is adapted to be moved downward yieldingly while rotating in order to advance and rotate a bolt for the purpose of screwing it into a nut. Splined to the spindle 120, so as to compel the spindle to rotate with it, but permit it to slide longitudinally, is a pulley 121, shown as a small grooved pulley contacting with the adjacent separated faces of the bearing portions of arms 119. Pulley 121 is rotated from the main shaft 104, by means of a belt connection 122, to a driving pulley 123 secured to said shaft 104; said belt passing over two idler pulleys 124, supported by a bracket 125 pivoted at 126 between two lugs 127 on the post 103, whereby the direction is changed as illustrated. The said belt may be tightened by adjusting the bracket 125, by means of screws 128 threaded through the bracket and bearing upon the upper end of the post. The belt drive described, comprising the relatively small pulley 121, rotates the spindle 120 with a yieldable friction drive. If the spindle encounters great resistance, as in the case of imperfect threads on bolt or nut, or too small a hole in the nut, the belt will slip on pulley 121, the other parts of the machine go on operating and the imperfect bolt and nut be ejected as will later appear.

The cam 117, before mentioned, is a part of the mechanism for reciprocating spindle 120. Secured to the upper end of said spindle is a grooved collar 129. A bell crank 130

lever 130 pivoted at 130^a to column 118 has a forked end 131 provided with studs 132 for engaging in the groove of collar 129, whereby up and down movement of the forked end 5 of lever 130 will impart up and down movement to spindle 120. On the side of column 118 that is adjacent the wheel 108 and cam 117 is a slide bearing 133 the sides of which are slotted at 134. Slidably mounted in said 10 slide bearing is a slidable member 135, the inner end of which is pivoted to the lower end of bell crank lever 130 as indicated in dotted lines at 136. The other end of slide 135 carries a roller 137 pivoted in a slot in 15 the slide which registers with the slots 134 in the bearing 133. A spring 138 tends to pull the forked end of the bell crank lever downward to advance the spindle 120 yielding, and to simultaneously urge the roller 137 into contact with the cam 117 which 20 operates to move the spindle 120 positively upward.

In order to position a bolt in line with the bolt socket on the lower end of spindle 25 120, a bolt receiver and conveyer is provided, said bolt conveyer comprising in this instance an oscillatory arm 139 which may be integral with or rigidly connected to a sleeve 140 splined to an upright spindle 140^a 30 rotatably mounted in bracket 140^b bolted to the base 101 adjacent the foot of column 118. The said arm 139 extends outward and downward and has projecting laterally from its outer end a block 141 having a V-shaped 35 notch 142 adapted to engage and center the shank of a bolt. Secured to the under side of block 141 is a slotted plate 143 the sides of which project slightly beyond said block. This plate 143 is for the purpose of 40 engaging over the nut with which said bolt is to be assembled and holding said nut down squarely on its seat while the centering pin to be hereafter described engages said nut, and the end of the bolt enters it. The end 45 of arm 139 is perforated to receive a pin 144 which may be held in adjusted position in the perforation by a set screw 145. A block 146 is detachably secured to pin 144 by set screw 147, and may be raised or lowered with 50 respect to the arm 139 by adjusting the pin 144, in order to adapt the carrier to bolts of different lengths; and if extra long bolts are being assembled a longer pin 144 may be secured to said block 146. Hinged to the 55 upper part of block 146 is a bolt receiving or landing plate 148. The outer end of landing plate 148 is notched at 149 to engage the shank of a bolt beneath the head thereof and allow the head to rest upon the upper surface of said plate. The inner end of the landing plate has two spaced ears 150, one on each side of the upper part of block 146. A hinge pin 151 passes through the ears 150 60 and the block 146, thus forming a horizontal pivotal connection between the landing plate

and block. A lug 152 projecting from the block 146 beneath plate 148 supports a coiled spring 153, which presses said plate yielding upward and allows the bolt to advance when it is engaged by the socket on advancing and rotating spindle 120 so that it may be screwed into the nut *n* with which it is to be assembled. A bolt *b* may be placed in the conveyer, either automatically or by hand, the head of the bolt resting on the outer end of landing plate 148, and its shank being steadied by the notch 149 in said plate and the V-shaped notch 142 in block 141. 70 Rising from the base 101 is a support 154 for a bolt positioning stop or anvil 155 adjustable therein, one end of said stop being so positioned that the conveyer will move the shank of the bolt against the stop to align the bolt with the spindle 120 and the center of the nut *n* with which it is to be assembled. The V-block 141 of the carrier and the end of the stop 155 are in such relation that the center of the stop comes opposite the center of the V-notch in the block 141 when the conveyer carries the bolt into contact with the end of the stop. The spindle 120 when advancing pushes the rotating bolt into engagement with the nut, the V-block 141 and stop 155 keeping the bolt in exact alinement. 75

The means for oscillating the bolt conveyer arm 139 comprises the arm 156 secured to spindle 140^a and connected by a pin and slot connection 157 to one end of a slide 158, the other end of which is similarly connected to a transmitting member 159 within the column 118; a slide 161 connected to said member 159, said slide carrying at its other end a roller 163 disposed in the path of a cam 164 on the gear wheel 108; and a compression spring 165 tending to push the member 159 in such a direction as to keep the roller 163 against the cam and urge the bolt conveying arm 139 toward the stop or anvil 155. By this mechanism the bolt *b* will be moved laterally yielding into alinement with the spindle 120, so that no harm can result by reason of any obstruction during the operation of moving a bolt into position to be assembled. 90

The nuts *n* to be assembled with the bolts slide down the nut run 116^a in succession under the influence of gravity, the foremost nut coming to rest in the nut seat 166 at the lower end of the nut run directly beneath the lower end of spindle 120, the sides of the nut seat being formed to fit the nut loosely but in such manner as to prevent it from being rotated by the bolt in the assembling operation. The bottom of the nut seat 166 has a central opening below which is a guide 167 for guiding a taper-end nut centering pin 168, which moves upward after a nut has reached the seat, the taper end entering a hole in the nut and centering it. The axis 110 115 120 125

of the centering pin is in the extension of the axis of spindle 120, and all properly punched and threaded nuts, even if the threaded hole is eccentric to the body, will thereby be brought with their threaded holes into alignment with the threaded end of the bolt to be assembled. The centering pin is operated by an arm 169 secured to one end of a rock shaft 170 extending, as shown, substantially parallel with the main shaft 104, under the base plate 101, and sustained by suitable bearings 171. Secured to the opposite end of rock shaft 170 is an arm 172, to which a vertical link or slide 173 is connected, said link or slide being guided by the bearing in the base plate 101 and normally held elevated by a spring 174 disposed between the upper surface of the base 101 and an adjustable collar 175, secured to said link or slide. Thus the spring 174 functions to draw the centering pin 168 downward out of nut engaging position. A sleeve 176 forms a telescoping extension of the link, and carries at its upper end a contact member 177 disposed so as to be engaged by a tappet or cam 178 on the face of gear 108. Within the sleeve 176 is housed a coil spring 179, of a resistance to compression that is greater than that of spring 174, said spring 179 having one end in contact with the upper end of slide 173 and its other end in engagement with a seat in the upper portion of sleeve 176. A pin and slot connection 180 limits the extent of possible sliding movement between the slide 173 and the telescoping sleeve 176. Contact of cam or tappet 178 with contact member 177 will normally positively advance the centering pin 168 to center a nut in correct time relation with respect to other operations of the mechanism. Should the end of the pin 168 encounter an unpunched blank or an excessively distorted nut so that the centering pin meets a solid obstruction, owing to the fact that nut holding plate 143 is then above the nut the spring 179 would yield and the machine continue its operation unharmed.

After a bolt and nut have been assembled and the spindle 120 has retreated from engagement with the bolt head, a plunger 181 engages the bolt just underneath the landing plate 148 and pushes the assembled nut and bolt from assembling position making way for another pair to be assembled. The plunger 181 is suitably guided so as to move in a direction parallel with the main shaft 104 and bolt conveyer operating arm 158. Said plunger is engaged by the lower end of a lever 182 of the third order fulcrumed at 183 on one of the arms 119 that guide the spindle 120. A link 184 has one end pivoted to the lever 182 at 185 and the other end pivoted to a slide 186 which carries a roller 187 disposed normally in the path of a cam 188 on the face of gear 108. The roller

187 is maintained yieldably in contact with cam 188 by a coil spring 189, one end of which is connected to lever 182, and the other to the column 118. As a result of this connection an assembled bolt and nut will be positively ejected at the proper instant. 70

It has thus far been assumed that the bolt may be placed in the bolt conveyer by hand or otherwise. The machine disclosed in Figures 4 to 9 comprises a detachable bolt hopper and bolt run. This hopper and bolt run will be used except when the machine is operating on peculiarly formed bolts not adapted to be well handled by the hopper and run, which are, except in minor particulars, substantially like the corresponding parts of the mechanism illustrated in Figures 1, 2 and 3. The lower end of the bolt run 190 is shown in Figures 5, 6, 8 and 9. The said run is steeply pitched so that the bolts will readily slide downward suspended by their heads on the spaced members of the runway. The lower end of the runway turns sharply at right angles curving horizontally and downward, presenting its discharge end 191 opposite the notch 149 in the landing plate 148, so that bolts may be delivered from the runway to the landing plate with their shanks in the notch 149 and the under sides of their heads resting on top of said landing plate. In order to eject the lowest bolt in the run 190 into the said angular discharge portion an ejector 192 is placed in position and operated at the proper instant to strike the shank of the bolt a little beneath the runway and push it into the angularly directed guide toward the discharge end 191. The ejector 192 is secured to one end of a plate 193 the other end of which is sleeved over a rod 194 the extremity of which is provided with a head or nut (not shown) between which and the plate a coiled compression spring 195 surrounds the rod 194, precisely as shown in the form of the invention disclosed in Figures 1 and 2, and for the same purpose, namely, to eject the lowermost bolt with a yielding thrust so that the machine will not be injured in case the ejector meets with abnormal resistance. In the present embodiment the other end of rod 194 is pivoted to lever 196 fulcrumed between its ends to the column 118 at 196a, and having its upper end pivoted to a link 197 which is connected to a lever 198, pivoted at 199 to a bearing bracket 200 projecting from column 118, and carrying a roller 201 at its upper end arranged to be engaged by the cam 117 so that the operation of the plunger to eject the bolt from the runway will take place after the retraction of the spindle 120 by the operation of said cam. The advance of the ejector is positively effected by the cam 117 except as modified by the compression spring 195 when the plunger meets abnormal obstruction. A com- 115 120 125 130

pression spring 202 causes the roller 201 to move into the path of cam 117 and the plunger 192 to retract.

Having described my invention in such manner as to enable those skilled in the art to which it appertains to make and use the same, what I claim and desire to secure by Letters Patent of the United States is:

1. In mechanism of the class described, a bolt rotating device having a bolt head receiving socket provided with ribs diverging forward at such an angle as to bite into the side of a bolt head and hold it from rotating with respect to said socket. 10
2. In mechanism of the class described, a bolt rotating device having an outward flaring conical socket provided with divergent biting ribs for engaging the side of a bolt head, and a central spring-pressed plunger 20 provided with a cup-like seat in its end for engaging a round bolt head seated in said socket, the end of said plunger being normally projected beyond the front of the socket. 25
3. In mechanism of the class described, a longitudinally movable and rotatable spindle having a bolt engaging means at one end, means for advancing said spindle with a yielding pressure, means for rotating said spindle simultaneously with its longitudinal movement, and means for positively retracting said spindle. 30
4. In mechanism of the class described, a longitudinally movable and rotatable spindle having a bolt engaging means at one end, means for causing said spindle to advance with a yielding pressure, means for positively retracting said spindle, and frictional driving means for rotating said spindle. 35
5. In mechanism of the class described, a longitudinally movable and rotatable spindle having a bolt engaging means at one end, means for rotating said spindle, a lever for moving said spindle longitudinally, means 40 exerting a yielding pressure upon the lever to move it in a direction to advance the spindle, and a cam arranged to operate the lever so as to withdraw the spindle positively. 45
6. In mechanism of the class described, a base, an upright column, a vertical spindle supported by said column, a friction pulley splined to said spindle, a lever fulcrumed on said column adapted to move said spindle longitudinally, a main driving shaft, a cam 50 driven from said main driving shaft, means arranged to engage the cam for operating the lever to retract said spindle, a device exerting a yielding pressure upon said lever to advance said spindle and maintain the lever in operative relation to the cam, and a means for rotating the spindle. 55
7. In mechanism of the class described, a base, a column rising therefrom, an upright spindle supported by said column, a horizontal power shaft, a cam operated thereby, 60 a bell crank lever pivoted in the column for moving said spindle longitudinally, connections from said lever to engage said cam for retracting the spindle, a spring acting upon said lever to advance the spindle and keep the lever in operative relation to the cam, a pulley splined on said spindle so that the latter may slide therethrough, a pulley on the main power shaft, idle pulleys, and a belt passing over said idle pulleys arranged 65 to transmit motion from the main power shaft to the spindle. 70
8. In mechanism of the class described, a nut seat adapted to hold a nut loosely but prevent it from being rotated, a centering pin adapted to be projected into said seat, a bolt rotating means axially alined with said centering pin, and means for effecting an approach between the bolt rotating means 75 and the nut seat. 80
9. In mechanism of the class described, a movable centering device for centering a nut, mechanism for advancing said centering device to engage and center the nut, and a yieldable connection in said mechanism. 85
10. In mechanism of the class described, means for holding two elements consisting of a bolt and nut in axial alinement, said means comprising a seat yieldable axially of the bolt and means for rotating said elements relatively to each other, means for advancing said rotating means into engagement with the elements to be rotated in order to screw said elements together, and means for retracting said rotating element after the bolt and nut have been assembled. 90
11. In mechanism of the class described, a socket adapted to hold a nut and prevent it from rotating, a bolt holder comprising means for holding a bolt in axial alinement with said nut, said bolt holder having a bolt sustaining member yieldable toward the nut socket, and a bolt rotating means arranged to advance along the axial line of a bolt and nut held in said socket and holder to engage the head of said bolt and screw it into the nut, and means for retracting said bolt rotating means. 100
12. In mechanism of the class described, a movable device for centering a nut, means for operating said device comprising a positive actuator, transmission means therefrom to the centering device, said transmission means including a spring adapted to yield in case the centering device meets with 105 abnormal obstruction. 110
13. In mechanism of the class described, a movable device for centering a nut, means for operating said device comprising a positive actuator, transmission means therefrom to the centering device, said transmission means including a spring adapted to yield 115 in case the centering device meets with ab- 120
- 125

normal obstruction, and a yieldable pressure device adapted to restore the centering device to its inoperative position.

14. In mechanism of the class described, a movable device adapted to center a nut, a cam; a device in the path of the cam comprising a telescoping slide and a spring tending to elongate said slide; and a rock shaft connecting said slide and said centering device.

15. In mechanism of the class described, a nut seat adapted to hold a nut horizontally, a centering pin adapted to move upward into said seat in order to center a nut, a rock shaft for operating said centering pin, a slide for operating said rock shaft, said slide having telescoping members and a spring adapted to elongate them, cam mechanism adapted to move the slide and elevate the centering pin, and a spring tending to press said slide into the path of the cam and retract the centering pin.

16. In mechanism of the class described, an ejector mechanism and operating means therefor comprising a yieldable connection, and mechanism for positively actuating the operating means to effect the ejecting operation.

17. In mechanism of the class described, a bolt runway adapted to convey bolts by gravity with their shanks depending; an ejector adapted and arranged to push a bolt from the lower end of said runway, means for actuating the ejector to push the bolt from said runway, said means comprising a yieldable connection adapted to yield in case the ejector meets with abnormal obstruction.

18. In mechanism of the class described, an inclined runway comprising a slotted guide adapted to hold bolts suspended by their heads, said runway having a discharge opening at right angles to its general direction, and an ejector adapted and arranged to push a bolt laterally through said discharge opening.

19. In mechanism of the class described, an inclined runway comprising a slotted guide adapted to hold bolts suspended by their heads, said runway having a discharge opening at right angles to its general direction, a plunger adapted to engage the bolt beneath the runway at the discharge end and eject the bolt therefrom, a plate connected to said plunger, a rod freely slidable through the plate, and an elastic connection between said rod and said plate, and means for positively actuating said rod for moving the plunger against the bolt to eject it.

20. In mechanism of the class described, a bolt conveyer adapted to move a bolt from receiving to assembling position, and then return; said conveyer comprising a device having a yieldable notched member adapted to embrace the shank and support the head

of a bolt, and a notched block adapted to engage and center the shank of the bolt, a stop device disposed in the path of movement of said notched block, and a yieldable pressure means for moving the conveyer from the receiving position to bring the shank of a bolt against the said stop.

21. In mechanism of the class described, a bolt conveyer movable from receiving to assembling position and comprising aligned bolt holding and centering devices adjustable to and from each other to adapt the conveyer for different lengths of bolts.

22. In mechanism of the class described, a bolt conveyer comprising an arm having a V-block projecting laterally therefrom, and a vertically adjustable downward yieldable notched landing plate adapted to support the bolt by its head with its shank in engagement with said V-block.

23. In mechanism of the class described, a conveyer arm having an offset V-block adapted to center the shank of a bolt, said arm having a perforation, a pin adjustable in said perforation, and a vertically yieldable landing plate connected to said adjustable pin above said V-block.

24. In mechanism of the class described, a bolt conveyer member carrying a V-block adapted to center the shank of a bolt, said member having a perforation, a pin adjustable in said perforation, and a member having a bolt head sustaining means detachably connected to said pin.

25. In mechanism of the class described, a bolt conveyer device carrying a V-block adapted to center the shank of a bolt and a bolt head supporting member pivoted to the conveyer device and having a bolt seat aligned with said notch; and a spring tending to move the free end of said bolt head supporting member away from the V-block.

26. In mechanism of the class described, a bolt conveyer adapted to move a bolt laterally to assembling position, a stop arranged to engage the shank of the bolt and center it in assembling position.

27. In mechanism of the class described, a bolt conveyer adapted to move a bolt laterally from receiving to assembling position, a stop, means tending to move the conveyer yieldingly to bring the bolt against said stop, and means adapted positively to return the conveyer to initial position.

28. In mechanism of the class described, means to hold a nut loosely but prevent it from rotating, a bolt conveyer adapted to move a bolt laterally into alignment with a nut on said nut holder, said bolt conveyer being adapted to move in a direction of the axis of the bolt resting therein permit the bolt to be advanced into contact with the nut, means for rotating and advancing the bolt to assemble it with the nut, and a device on the conveyer adapted to hold the nut to its

seat until the end of the bolt has entered the nut.

29. In mechanism of the class described, the combination of a nut holder, a longitudinally movable and rotary spindle in axial alinement with the nut holder, said spindle having a bolt centering and rotating member in its end, and means for centering a bolt in the axial line of said spindle and nut holder in position to be engaged by the spindle as the latter advances.

30. In mechanism of the class described, the combination of a nut holder, an upright longitudinally movable and rotatable spindle in axial alinement with the nut holder, said spindle having means to engage and rotate a bolt when pressed against it and to automatically release the bolt when retracted, means for holding a bolt in axial alinement with said spindle and said nut holder, and an ejector device operating in timed relation with the spindle to eject the assembled nut and bolt laterally after retraction of the spindle.

31. In mechanism of the class described, the combination of a nut holder and nut centering device, of an upright longitudinally movable and rotatable spindle in axial alinement with the nut centering device, a bolt holder adapted to center a bolt in the axial line of the spindle and nut centering device; means for rotating and advancing the spindle so as to engage the bolt head and subsequently retract said spindle and release it from the bolt, and an ejector mechanism arranged to operate after the retraction of the spindle for ejecting the assembled nut and bolt laterally.

32. In mechanism of the class described, the combination with a bolt run, of means for removing bolts one by one from the discharge end of said bolt run; a longitudinally movable and rotatable spindle, a nut holder in line therewith, and means for receiving a bolt removed from the bolt run and moving it into axial alinement with the spindle and nut holder said means having a bolt head engaging member yieldable in the direction of the bolt axis whereby the advancing spindle may seize the bolt head and assemble said nut and bolt.

33. In mechanism of the class described having a bolt rotating means, a bolt run-

way, an oscillatory conveyer movable from a receiving position adjacent the discharge end of the bolt run to a position where the bolt may be engaged by the bolt rotating means, said conveyer having a yielding notched landing plate adapted to receive and sustain the bolt in an upright position by its head.

34. The combination of a gravity bolt run, a nut holder and a bolt rotating means; a bolt conveyer movable from a position in juxtaposition to the discharge end of the bolt run to a position in which the bolt is aligned with said nut holder and bolt rotating means, said conveyer having a notched landing plate pressed upward by a spring and a centering guide beneath the landing plate whereby the bolts may be centered, and means for moving said conveying means back and forth between the receiving position and the assembling position.

35. In mechanism of the class described, a nut holder, a bolt rotating means, a centering device adapted to center the nut into line with the axis of the bolt, and a movable member adapted to engage over the nut during the centering movement of the centering device.

36. In mechanism of the class described, a nut holder, a nut centering device, a bolt rotating device, a bolt conveyor adapted to move a bolt into line between the nut holder and bolt rotating device, and a member movable with the bolt conveyor, adapted to engage over the nut, during the centering movement of the centering device.

37. In mechanism of the class described, a nut holder, a nut centering device, a bolt rotating spindle in line therewith, an oscillatory conveyer adapted to move a bolt laterally into line between the bolt rotating spindle and the centering device, said conveyer having a divided member extending each side of the bolt shank and adapted to engage over the nut during the centering movement of the centering device.

38. In mechanism of the class described, a nut holder, a centering pin, a member adapted to engage over the nut during the centering operation, and means for advancing the centering pin with a yielding pressure to center the nut.

In testimony whereof I affix my signature.
THOMAS EYNON.
